Inventor
Joseph E. Auclair

Watson & Colman
Attorney

UNITED STATES PATENT OFFICE.

JOSEPH E. AUCLAIR, OF STAMFORD, CONNECTICUT.

PORTABLE DOG.

Application filed June 11, 1921. Serial No. 476,877.

To all whom it may concern:

Be it known that I, JOSEPH E. AUCLAIR, a citizen of the United States, residing at Stamford, in the county of Fairfield and State of Connecticut, have invented certain new and useful Improvements in Portable Dogs, of which the following is a specification, reference being had to the accompanying drawings.

10 This invention relates to devices of that character which are used for holding doors closed, window sashes from being opened, and used by carpenters for the purpose of holding one timber abutted against another.

15 The general object of my invention is to provide a device of this character which is of very simple, cheap construction, and which may be used for a large variety of purposes, and which when in use will hold 20 two parts from shifting relative to each other.

A further object is to provide a device of this character which is made from one piece of metal and which is very strong and 25 thoroughly effective for the purposes stated.

My invention is illustrated in the accompanying drawings, wherein:—

Figure 1 is a top plan view of my improved holding dog;

30 Figure 2 is a side elevation of the same;

Figure 3 is a fragmentary view of a window showing my holding dog applied thereto;

Figure 4 is a fragmentary view illustrating 35 the manner in which the holding dog is applied to hold a door from movement;

Figure 5 is a fragmentary vertical section of window sashes showing how my dog is applied thereto.

40 Referring to these drawings, it will be seen that my improved dog is made from a flat strip of mild steel about $\frac{1}{8}$ " thick, $4\frac{1}{2}$ " long and $1\frac{1}{4}$ " wide, this strip 10 at one end being slightly curved downward, as at 11, 45 beveled upon its upper surface, as at 12, and provided with teeth 13. The opposite end of the strip is left of its full thickness but serrated to provide teeth 14 which extend entirely across the end edge of the strip. The blank from which this dog is made is formed with two slots 15 extending inward and toward the teeth 14, these slots

terminating approximately an inch from the teeth 14 and the metal exterior to the slots is bent downward to form prongs 16, 55 these prongs gradually tapering toward their lower ends and sharpened to a point. It will be seen that with this construction the prongs 16 may be forced into the floor, 60 plank or timber and that if then force be applied against the serrated edge 14, the teeth 13 will bite into the wood or other material against which the teeth are placed, the prongs 16 acting as a fulcrum for the dog. 65

This dog can be used as a door fastener or door jam by placing the short end of the dog against the door, the teeth 14 confronting the door, and the prongs 16 rest upon the floor or forced slightly into the floor. 70 Then if anyone attempts to open the door, the force exerted against the dog will cause the teeth 13 to be forced into the floor and the dog will hold and prevent the door from being opened. It may be also used 75

as a sash fastening device. By placing the dog upside down on top of the lower sash, the teeth 14 against the lower sash, and the teeth 13 against the upper sash, then if any effort be made to open the lower sash, the teeth 13 will be forced into the upper sash 80

and vice versa. It may also be used by floor layers as a dog for holding the planks of the floor in place while they are being nailed. The dog can be placed anywhere on 85

the floor and the end of a board be abutted against the front teeth of the dog, which will thus hold the boards from any sliding or shifting movement, rendering it easy to fit the piece of flooring. It is adapted to a 90 number of other uses, and indeed anywhere where it is desired to hold a member from moving relative to another member.

I claim:—

1. A dog of the character described comprising a body formed of a relatively thin strip of metal, one end of the body being slightly bent and beveled and formed with teeth, the opposite end of the body having teeth, and prongs projecting at right angles 95 to the body and forming a fulcrum therefor, said prongs being disposed adjacent the last named set of teeth. 100

2. A dog of the character described hav-

ing a body formed of thin metal, the body having a pair of slits extending inward and toward one end of the body and formed to define laterally disposed prongs, said prongs being bent downward at approximately right angles to the body and pointed, that end of the body adjacent said

prongs being serrated, the opposite end of the body having its outer face beveled and its under face slightly curved downward 10 and the edge serrated.

In testimony whereof I hereunto affix my signature.

JOSEPH E. AUCLAIR.
